CLAIM

What is claimed is the ornamental design for a headwear with fiber optic tufts, as shown and described.

DESCRIPTION

FIG. 1 is a perspective view of a headwear with fiber optic tufts, showing the new design in a deployed configuration; FIG. 2 is a front elevational view thereof, the rear elevational view being a mirror image thereof;

FIG. 3 is a left-side elevational view thereof, the right-side elevational view being substantially a mirror image thereof, the only difference being the slight variability in the positions of the filaments comprising the fiber optic tufts;

FIG. 4 is a top plan view thereof;

FIG. 5 is a bottom plan view thereof;

FIG. 6 is a perspective view thereof, illustrated in a collapsed configuration;

FIG. 7 is a left-side elevational view thereof, the right-side elevational view being substantially a mirror image thereof, the only difference being the slight variability in the positions of the filaments comprising the fiber optic tufts;

FIG. 8 is a front elevational view thereof, the rear elevational view being a mirror image thereof;

FIG. 9 is a top plan view thereof; and,

FIG. 10 is a bottom plan view thereof.

The broken lines showing a person in FIG. 1 are included for the purpose of illustrating the invention in use, and form no part of the claimed design. The slight variability in the positions of the filaments comprising the fiber optic tufts shown in the drawings is due to the nature of the filaments themselves, and is not illustrative of deliberate differences in structure.
